UNITED STATES PATENT OFFICE.

JAMES G. BLUNT, OF SCHENECTADY, NEW YORK.

LATERAL-MOTION DEVICE FOR LOCOMOTIVE DRIVING BOXES.

Application filed November 19, 1927. Serial No. 234,322.

This invention relates to lateral motion devices, and has for an object to provide a device of such character, particularly adapted for application to the driving boxes of locomotives of the outside bearing type, and which will exert a resistance, acting to hold the driving boxes in normal central position on tangent track, the resistance being sufficiently yielding to permit a limited lateral movement of the driving boxes to accommodate the locomotive to curved track, and to enable the locomotive to absorb the violent lateral stresses incident to service.

The improvement claimed is hereinafter fully set forth.

In the accompanying drawings: Figure 1 is a side view, in elevation, of a locomotive embodying the invention; Fig. 2, a fragmentary view, in side elevation, showing the application of the mechanism; Fig. 3, a view, in perspective, of one of the rockers; Fig. 4, a plan view, partly in section, of the construction shown in Fig. 2; and, Fig. 5, a front view, partly in elevation, and partly in section, thereof.

In the practice of the invention, referring descriptively to the specific embodiment thereof which is herein exemplified as applied in an electric locomotive of the outside bearing type, comprising two articulated trucks, each having six driving wheels, the driving boxes, 10, of each of the outer driving axles, 11, of the trucks, are slidably fitted in pedestal jaws, 12, of the truck frames, 13, suitable shoes, 14, being provided on the jaws, to take up for wear. Each driving box is formed, at each side, with a pair of vertical laterally projecting flanges, 15, which retain and guide the boxes in the pedestals. Sufficient clearance is provided, between the flanges and the shoes, to permit the necessary lateral movement of the boxes, to accommodate the locomotive to curved track.

A spring saddle, 16, for a plate spring, 17, is mounted on each of the driving boxes.

The outer face of each of the side frame members of the truck is integrally formed, above the pedestal jaws, with two spaced knuckles, 18, having aligned bores for the reception of a shaft, 19, which serves as a fulcrum for the rocker lever, 20. The lever

is bifurcated, and each of its legs, 20^a, is provided, on each side, with a hub, 20^b, to increase the bearing on the shaft. The lower end of each leg of the lever, is bifurcated, to provide two spaced knuckles, 20^c, between which is fitted, on the pin, 20^d, a roller, 20^e. The bifurcated ends of the lever are spaced a sufficient distance apart, so that the rollers, 20^e, bear on the side flanges, 15, of the driving box. This construction permits the driving box to rise and fall relatively to the frame. Each leg of the lever is formed, below the hubs, with a projection or stop, 20^f, adapted to abut against the front face of the side frames, to positively limit the travel of lower ends of the lever in one direction, for the purpose of storing power in a spring device, which will be described hereinafter.

The legs of the lever converge upwardly, and are united, near their upper ends, by a bridge piece, 20^g. Each lever is formed, at its top, with two spaced lugs, 20^h, which extend above the bridge piece, and are spaced apart to provide a socket, 20ⁱ, for the reception of an end of a thrust rod, 21.

Fitted on each end of the thrust rod, is a pair of spring seats, 22 and 23, between the members of each pair of which is interposed a helical spring, 24. The outer spring seats, 22, are slidably fitted on the rod, and each is provided with a pair of concave recesses, in which are fitted the rounded upper ends of the lugs, 20^h, of the levers. The inner spring seat, 23, at one end of the rod, is held against inward sliding movement on the rod, by a shoulder, 25, while the other inner spring seat is slidably mounted on the rod, so that it may be adjusted by the nut, 26, to vary the compression of the springs, as desired. A lock nut, 27, is provided to hold the nut, 26, in its adjusted positions.

The operation of the appliance is as follows:

When the appliance is installed, the nut, 26, is adjusted to give the springs sufficient compression to tilt the levers inwardly, causing the rollers thereon to bear, with sufficient force, on the driving boxes, to hold them central with the side frame members on tangent track, and the stops, 20^f, to contact with the side frame members. When the

locomotive enters curved track, lateral forces are encountered, of sufficient magnitude to overbalance the force of the springs, and cause the driving boxes to move laterally of the side frame members, to accommodate the wheels to the track. This movement of the driving boxes will cause the one moving outwardly of its side frame member, to tilt its associated lever outwardly, and as the other lever is held from inward movement by its stop, 20', bearing on the adjacent side frame member, the springs, 24, will be additionally compressed to store sufficient power to enable the outwardly moved lever to restore the driving boxes to their normal central position, when the locomotive re-enters tangent track.

An additional important advantage of the described appliance is that it operates efficiently to absorb any violent lateral stresses which may be encountered in service.

The invention claimed as new and desired to be secured by Letters Patent is:

1. In a locomotive of the outside bearing type, the combination of a plurality of pairs of driving wheels; an axle for each pair of wheels, having journals disposed outside of the wheels; a frame, comprising two side frame members supported by the journals; pedestals in said side frame members; driving boxes mounted on the journals and fitted in the pedestals, with the capacity of a limited lateral movement; a lever, fulcrumed at the outerside of each side frame member, and having a lower leg disposed below the fulcrum, adapted to bear on an adjacent driving box, and an upper leg disposed above the fulcrum; and means, associated with the upper legs of a pair of levers, disposed on opposite sides of the frame, said means being adapted to store sufficient power when one of the levers is tilted by an outward lateral movement of a driving box, to cause the tilted lever to restore the outwardly moved driving box to normal position, when the force causing such outward lateral movement is removed.

2. In a locomotive of the outside bearing type, the combination of a plurality of pairs of driving wheels; an axle for each pair of wheels, having journals disposed outside of the wheels; a frame comprising two side frame members supported by the journals; pedestals, in said side frame members; driving boxes, mounted on the journals, and fitted in the pedestals, with the capacity of a limited lateral movement; a lever, fulcrumed at the outerside of each side frame member, and having a lower leg, disposed below the fulcrum, adapted to bear on the adjacent side frame and the adjacent driving box, and an upper leg, disposed above the fulcrum; and means, associated with the upper legs of a pair of levers, disposed on opposite sides of the frame, said means embodying a

helical spring, and being adapted to store sufficient power in said spring, when one of the levers is tilted by an outward lateral movement of a driving box, to cause the tilted lever to restore the outwardly moved driving box to normal position, when the force causing such outward lateral movement is removed.

3. In a locomotive of the outside bearing type, the combination of a plurality of pairs of driving wheels; an axle for each pair of wheels, having journals disposed outside of the wheels; a frame comprising two side frame members, supported by the journals; pedestals, in said side frame members; driving boxes mounted on the journals, and fitted in the pedestals, with the capability of a limited lateral movement; and means, exerting a yielding resistance, adapted to hold the driving boxes in normal central position, relatively to the side frame members, when the locomotive is traversing tangent track, and to permit a limited lateral movement of the driving boxes, when the locomotive is traversing curved track, said means comprising a pair of levers, one fulcrumed at the outer side of each of the side frame members, each lever having a lower leg, disposed below the fulcrum, adapted to bear on the adjacent side frame member, and on an adjacent driving box, and an upper leg, disposed above the fulcrum; a rod, disposed transversely of the frame; a pair of spring seats at one end of the rod, one of the spring seats being normally held in fixed position on the rod, and the other spring seat being freely slidable therewith, one of the spring seats being adapted to bear on the upper leg of one of the levers; means for adjusting the position of at least one of the spring seats with relation to the other; and a helical spring interposed between the seats and normally held under compression thereby.

4. In a locomotive of the outside bearing type, the combination of a plurality of pairs of driving wheels; an axle for each pair of wheels, having journals disposed outside of the wheels; a frame, comprising two side frame members supported by the journals; pedestals in said side frame members; driving boxes, mounted on the journals, and fitted in the pedestals, with the capability of a limited lateral movement; and means, exerting a yielding resistance, adapted to hold the driving boxes in normal central position, relatively to the side frame members, when the locomotive is traversing tangent track, and to permit a limited lateral movement of the driving boxes, when the locomotive is traversing curved track, said means comprising a pair of levers, one fulcrumed at the outer side of each of the side frame members, each lever embodying a pair of lower legs, disposed below the fulcrum, and an upper leg disposed above the fulcrum, a stop on each of the lower legs, adapted to bear on the

outerside of the adjacent side frame member, and a roller mounted at the lower end of each of the lower legs, and bearing on the adjacent driving box; a thrust rod disposed transversely of the frame; a pair of spring seats at each end of the rod, the outer spring seats being slidably mounted on the rod, and hav-

ing means engaging the upper ends of the levers, the inner spring seats being normally fixed on the rod; a helical spring between the members of each pair of seats; and means for adjusting at least one of the inner seats. 10
